(57) **CLAIM**

The ornamental design for a saw base plate work-piece protector, as shown and described.

DESCRIPTION

FIG. 1 is a front view of a saw base plate work-piece protector showing an embodiment of my new design.

FIG. 2 is a rear view thereof.

FIG. 3 is a right side view thereof. The left side view is a mirror image of the right side.

FIG. 4 is a top view of thereof.

FIG. 5 is a bottom view thereof.

FIG. 6 is a perspective view thereof.

FIG. 7 is a front view of a saw base plate work-piece protector showing an embodiment of my new design with side and rear relief to provide clearance for saw adjustment.

FIG. 8 is a rear view thereof.

FIG. 9 is a right side view thereof.

FIG. 10 is a left side view thereof.

FIG. 11 is a top view of thereof.

FIG. 12 is a bottom view thereof; and,

FIG. 13 is a perspective view thereof.
